Primary Examiner — Catherine S Posthauer*Assistant Examiner* — Amanda Christensen(74) *Attorney, Agent, or Firm* — Patterson + Sheridan LLP(57) **CLAIM**

The ornamental design for a chamber inlet, as shown and described.

DESCRIPTION

FIG. 1 is a top plan view of a chamber inlet showing our new design; and,

FIG. 2 is a top, right side perspective view of the chamber inlet of FIG. 1, shown enlarged for clarity of disclosure. The broken lines depict portions of the chamber inlet that form no part of the claimed design.

1 Claim, 1 Drawing Sheet(56)
